DETENTION WINDOW

Lee Bayley, Springfield, Ohio, and Robert L. Clingerman, Washington, D. C., assignors to The William Bayley Company, Springfield, Ohio, a corporation of Ohio

Application February 25, 1930. Serial No. 431,117

11 Claims. (Cl. 189—64)

Our invention relates to window sashes and more particularly to metallic window sashes especially adapted for jail and reformatory use, but also applicable to other installation wherein it is desirable to provide ventilating openings protected against entrance or escape.

In the present invention there is contemplated a structural steel window sash of large proportions such as are commonly employed in factory and 10 warehouse construction, the transversely disposed mullion bars of which are comparatively closely spaced to afford a grating or grille having numerous small spaces, certain of which are closed by window panes leaving a group of such spaces to 15 afford a ventilating opening across which the sash mullions extend. This affords within the window sash structure a barred opening. Mounted at the interior side of such barred ventilating opening is an auxiliary sash adjustable relative to the main 20 sash and normally closing said opening. Actuator means for the closure sash are mounted exteriorly of the main sash and operatively connected with such closure sash through restricted openings in the fixed portion of the structure. 25 The barred ventilating opening is further provided with a screen upon its exterior side or that side opposite the closure.

The object of the invention is to simplify the structure as well as the means and mode of operation of ventilated windows for jails, reformatories, and the like, whereby they will not only be cheapened in construction, but will be more efficient in use, of increased durability and strength, and unlikely to get out of order.

35 A further object of the invention is to incorporate in a single structure the window guard or jail bars and the window sash structure whereby the sash mullions become duofunctional.

A further object of the invention is to provide a 40 compact structure of duofunctional character having a guarded or barred ventilating opening and to provide an adjustable closure for such opening.

A further object of the invention is to provide a 45 combination window sash and window guard or jail bar structure having a screened ventilating opening.

A further object of the invention is to provide in such a structure improved means for adjusting 50 the closure of the ventilating opening from the outside of the sash structure.

A further object of the invention is to provide a 55 window sash having glass openings too small for the passage of a man, and having therein a ventilating opening including the area of a number of such glass openings formed by the intersection of transverse mullion bars extending across such ventilating opening.

With the above primary and other incidental 60 objects in view, as will more fully appear in the

specification, the invention consists of the features of construction, the parts and combinations thereof, and the mode of operation or their equivalents as hereinafter described and set forth in the claims.

Referring to the accompanying drawings wherein is shown the preferred, but obviously not necessarily the only, form of embodiment of the invention, Fig. 1 is a front elevation of a window sash embodying the present invention.

Fig. 2 is a vertical sectional view of the window sash structure taken through the ventilating opening.

Fig. 3 is a transverse sectional plan view thereof also taken through the ventilating opening.

Like parts are indicated by similar characters of reference throughout the several views.

Referring to the accompanying drawings, 1 indicates a portion of the building wall in which is incorporated the structural steel sash 2. This 80 sash comprises a frame 3 divided by transverse interlocking mullions 4 into a plurality of comparatively small spaces 5. The mullions 4 are comparatively closely spaced, whereby the spaces 5 are entirely too small for a person to pass 85 through. Most of these spaces 5 are closed by panes of glass leaving a group of spaces 5' vacant to form a ventilating opening as shown at 6. The mullions 4, however, continue transversely both 90 vertically and horizontally across this ventilating space 6. The frame 3 and mullions 4 are formed of such material and so interlocked as to constitute jail bars or a grille which may not be easily broken. Thus the sash mullions 4 are duofunctional. These mullion bars 4 not only serve their 95 ordinary and usual purpose as parts of a window sash, but they also additionally function as jail bars.

Adjustably mounted interiorly of the main sash 2 and normally in registry with the barred ventilating opening 6, is an auxiliary closure sash 7. This closure sash may be of any suitable construction. It may be formed, as is the main sash, with transverse mullion bars or, as shown in the drawings, may consist of a sash frame 7 containing a single continuous glass window pane 8. The closure sash 7 is hinged at 9 to the interior of the main sash 2. This hinge joint is preferably, though not necessarily, located at the bottom of the sash, whereby such closure sash may be tilted inwardly and downwardly to open the barred ventilating opening 6. Surrounding the ventilating opening and welded to the mullion bars of the main sash is an angle frame 10 upon which the flanged frame 7 of the closure sash abuts to 115 form a tight joint. Located exteriorly of the main sash 2 is an operator shaft 12 extending transversely across the window opening and preferably, though not necessarily, continuing through the masonry pilasters 1 of the building structure 120

in which are embedded tubular sleeves or pipes 13 to receive such operator shaft. Adjacent to the barred ventilating opening 6 of the window sash the operator shaft 12 carries gear pinions 14 which mesh with arcuate rack bars 15 projecting through the main sash 2 and engaged with the adjustable closure sash 7. The sides of the sash frame 7 of such closure sash are preferably provided with arched ears or keepers 16 within which the ends of the rack bars 15 are pivoted. The glass panes in the spaces of the sash adjacent to the ventilating opening are notched at their corners to permit the passage of the rack bars 15. A cover plate or housing 17 is welded to the sash structure coincident with such notched window glass providing a keeper and enclosure for the rack bars. By thus positioning the operator shaft outside the sash structure, there are no projections nor apparatus within the building upon which the inmates may climb. It is quite impossible for anyone confined within the building to interfere with the operation of the window sash closure 7. The operator shaft 12 may be rotated by any suitable means as such rotation will effect a relative adjustment of the closure 7 at the opposite side of the main sash 2.

Disposed exteriorly over the ventilating opening 6 of the sash is a screen 18. This screen is mounted upon a suitable frame 19 enclosed within angle bars 20 welded to the mullions 3 about the ventilating openings. The screen being confined to the area of the ventilating opening, while the rack bars 15 pass through the window sash slightly beyond such opening, the sash operating mechanism does not interfere in any way with the screen.

While the ventilator closure has been shown on the inner side of the sash structure, it is obvious that if so desired it may be located upon the outer side of such sash and upon the same side with the operator mechanism. This would interpose the jail bar grille formed by the mullion bars intersecting the ventilating opening between the persons confined within the building and the closure sash 7. Thus interference with the operation of the closure would be further prevented.

The mullion bars and other members of the sash frame are of substantially conventional shape but are of somewhat increased dimensions in cross sectional area to agree with standard requirements for jail construction. The frame 8 of the closure sash is formed from standard sash bar section.

The sash 2 may be installed in the masonry in any suitable manner. The flanged margin of the sash frame may be projected into a suitable recess provided in the masonry wall as shown at the top of the window sash, which recess is subsequently filled with concrete or other plastic sealing material. Otherwise, the flanged margin of the sash frame may be bolted or riveted to anchor members embedded in the masonry structure as shown at the bottom in Fig. 2 or as shown in the detail view Fig. 3 wherein such margins are shown riveted to anchor members 21 embedded in the masonry wall.

As before mentioned the closure frame 7 preferably though not necessarily carries but a single pane of glass 8, which is substantially coextensive with the ventilating area of the main sash and is therefore common to and overlies a plurality of the spaces formed within the ventilating area by the intersection therein of the transversely arranged mullion bars. By making the glass 8 of the closure of comparatively large size,

it disguises somewhat the prison appearance of the structure. The closure sash 7 when adjusted to closed position recedes within a frame 10 fixedly secured to the main sash structure. It will be noted that the bottom member of this affixed closure frame 10 is upturned at 25 at its inner margin, and at its outer margin it overhangs the transverse mullion bar 3 defining the bottom of the ventilating opening. The sash 7 of the adjustable closure is formed of angle bar stock, one set of flanges 7a of which are out-turned substantially in the plane of the closure while the other set of flanges 7b are laterally disposed in the direction of the main sash structure. The outwardly projecting flanges 7a abut upon the inner flange margin of the affixed frame 10 while the laterally extending flanges 7b abut directly upon the mullion bars 4 of the main sash structure. This is true at both the top and the sides of the closure. However at the bottom of the closure a somewhat different construction prevails wherein the inwardly projecting flange 7b of the closure frame 7 is provided with a downwardly extending flange 24 which, in the present instance, is shown as an angle bar welded to the frame 7. This dependent flange 24 abuts in perpendicular relation upon the bottom frame member of the affixed frame 10 when the closure is in closed relation as shown in Fig. 2 of the drawings. It will be noted that at the bottom of the closure 105 the frame 7 abuts upon the upturned flange 25 of the frame 10 in a lateral direction, while the dependent flange 24 of the frame 7 abuts vertically upon the frame 10. The upturned inner flange 25 of the frame 10 forms an arresting dam for 110 water or seepage and prevents moisture from seeping through the closure joint. The flange 10 overhanging the mullion bar at the bottom of the ventilating area, as shown in Fig. 2, forms a water shed. The closure member making double 115 contact upon spaced contact lines is quite effective in excluding moisture and air when the ventilator is closed.

While the ventilating opening may, if desired, be located marginally relative to the main sash, 120 it is preferably located in a central or medial position, and is entirely surrounded by closed spaces. This is clearly apparent in Fig. 1, wherein the ventilating area is also illustrated as including multiple spaces both vertically and horizontally 125 formed by the intersection of the mullion bars 4 within such area. Cross reference is made to co-pending application Serial No. 496,709 filed November 19th, 1930 wherein is shown a somewhat different species of the present invention but involving common subject matter.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention is not limited to the specific details shown, but that the means and construction herein disclosed comprise the preferred form of several modes of putting the invention into effect and the invention is, therefore, claimed in any of its forms or modifications 145 150

within the legitimate and valid scope of the appended claims.

Having thus described our invention, we claim:

1. A window structure, transversely disposed 5 mullion bars dividing the window into a plurality of small spaces, window panes closing a portion of the spaces, a group of spaces being left open to afford a ventilating opening across which the mullion bars extend, closure means 10 for said barred opening and operating means at the outer side of the window for adjusting said closure means, said operating means including a housing for at least some of the movable parts thereof.
- 15 2. A window including transverse mullion bars, dividing the window into multiple spaces, window panes closing a portion of the spaces, a group of such spaces being left vacant to afford a ventilating opening across which the mullion 20 bars extend, an adjustable closure for the ventilating openings, an actuating shaft for said closure extending across the window and intersecting the window jambs at opposite sides of the window outside thereof, an operating connection between the shaft and closure, and a housing for the operating connection for protecting the same from the weather.
- 25 3. A detention window sash, including a plurality of mullions dividing the window into multiple spaces, window panes closing certain of the spaces and leaving a group of such spaces open to form a ventilating area, an adjustable closure located outside the window for said ventilating area, said closure having a double contact with the boundary of the ventilating area, operating means for the closure accessible at the opposite side of the sash, and a housing for said operating means to protect at least a part thereof from the weather.
- 30 4. A detention window sash, including a plurality of mullions dividing the window into multiple spaces, window panes closing certain of the spaces and leaving a group of such spaces open to form a ventilating area, an adjustable closure located inside the mullion bars for the ventilating area, closure adjusting means extending through the sash and operable from the side of the sash opposite the closure, and a housing for at least a part of said adjusting 45 means for protecting same from the weather.
- 50 5. A window including a plurality of transversely arranged muntin bars forming spaces some of which are glazed, leaving a ventilating area vacant across which the muntin bars extend, a closure pivotally attached adjacent the ventilating area, closure actuating means located on the opposite side of the window, said closure means including a pair of arcuate arms extending through openings provided therefor, 55 said arms being arranged to travel along an arcuate path extending through said openings.
- 60 6. A window including a plurality of transversely arranged muntin bars forming spaces some of which are glazed, leaving a ventilating area vacant across which the muntin bars extend, a closure pivotally attached adjacent the ventilating area on the inside of the window clo- 65
- sure, actuating means located on the outside of the window, said closure means including a pair of arcuate arms extending through openings provided therefor, said arms being arranged to travel along an arcuate path extending through said openings so as to track therethrough. 80
7. A window including a plurality of transversely arranged muntin bars forming spaces some of which are glazed, leaving a ventilating area vacant across which the muntin bars extend, a closure adjustably mounted adjacent the ventilating area, actuating means located on the opposite side from the closure, said actuating means including members extending through openings provided therefor in the window, said actuating means cooperating with the closure to cause said members to track through said opening. 85
8. A window including a plurality of transversely arranged muntin bars forming spaces some of which are glazed, leaving a ventilating area vacant across which the muntin bars extend, a closure movably mounted adjacent the ventilating area on the inside of the window, actuating means located on the outside of the window 100 and members extending through openings provided therefor for adjusting the position of the closure in response to movement of the actuating means, said members tracking through the opening when actuated by said means. 95
9. A window including a plurality of transversely arranged muntin bars forming spaces some of which are glazed, leaving a ventilating area vacant across which the muntin bars extend, a closure adjustably mounted adjacent the 110 ventilating area, means for actuating said closure located on the opposite side of the window and members attached to the closure extending through openings provided therefor in the window moving in response to movement of said actuating means, said actuating means cooperating with the closure to cause said members to track through said openings. 115
10. A window including a plurality of transversely arranged muntin bars forming spaces 120 some of which are glazed, leaving a ventilating area vacant across which the muntin bars extend, a closure pivotally attached to the other side of the window and adjacent the ventilating area, actuating means including members extending through openings provided therefor for opening and closing said closure, said actuating means cooperating with the closure in causing said members to track through said openings. 125
11. A window for a detention compartment including a glazed portion and an unglazed portion to afford a ventilating area, an adjustable closure for the unglazed portion interiorly thereof, an operator for adjusting the closure, and guard bars extending across the glazed and unglazed portions intermediate the detention compartment and the closure operator and duo-functionally serving to detain an occupant in the detention compartment and prevent tampering with the closure operator by such occupant. 130 135
